United States Patent Office.

JAMES D. SMITH, OF GREIG, NEW YORK.

Letters Patent No. 87,212, dated February 23, 1869; antedated February 15, 1869.

IMPROVEMENT IN MACHINE FOR GRINDING EDGE TOOLS.

The Schedule referred to in these Letters Patent and making part of the same.

To all whom it may concern:

Be it known that I, JAMES D. SMITH, of the town of Greig, in the county of Lewis, and State of New York, have invented certain new and useful Improvements in Machines for Grinding Edged Tools and other implements; and I do hereby declare that the following is a full, clear, and exact description of the same, reference being had to the accompanying drawings, making part of this specification, in which—

Figure 1 represents a front elevation of my machine, showing it applied in connection with a grind-stone.

Figure 2 is a top view of the same.

Figure 3 is a vertical section across the same.

Figure 4 is a detached vertical section of the tool-stock of the same, showing the manner of securing the edged tools on the stock.

Figure 5 is a rear elevation of a portion of the same.

Figure 6 is a perspective view of the clamp of the tool-stock of the same.

Similar letters of reference indicate corresponding parts in the several figures.

In implements for grinding the cutting-edges or other surfaces of tools, &c., it is, in many instances, of great importance to grind such edges to great accuracy; to have them as nearly straight as they can be made; or to have them with a certain curve; or to make a number of the same shape or curve, which is more particularly the case with the edges of planing-irons or shears, or shear-plates operating against guide-plates, where two faces have to meet with exactness; and the more particular object of my invention is to provide an instrument by means of which such tools or articles can readily be ground to great exactness in a very short space of time, and even when very-unskillful workmen are employed.

The nature of my invention consists in providing an instrument which may be readily attached, and used in connection with the grindstone, and to which the article to be ground is readily adjusted and secured at the proper or desired tangent or angle with the face or periphery of the stone, and which instrument or tool-stock is arranged to slide horizontally in front of the periphery of the stone, and is guided while sliding, so as to keep it in the relative tangential position, by means of a guide or pattern-bar connected therewith, and is provided with an automatic feeding-device, operated from the stone and its axle, in such a manner that the said article may be ground with precision by incompetent persons, and in a short space of time.

To enable others skilled in the art to make and use my invention, I will proceed to describe its construction and operation.

In the drawings, I have shown my device applied to the ordinary grindstone, of which A represents the stone; B, the grindstone-trough; C, the axle of the stone; D, the bearings; and E, the ordinary support-

bars, which are bolted to the trough, and are provided with the ordinary slots, to allow the rest to be adjusted to the periphery of the stone.

Upon the support-bars E, I secure the bed-plate F of my device, by means of bolts G, which pass through the said slots in the support-bars E, and through slots H, made in the bed-plate F, right-angular to the slots in the support-bars, to provide for the proper adjustment of the apparatus toward the periphery and face of the stone.

Now, my device for grinding consists of three vertical standards, I, I, and J, which may be cast on the bed-plate F, or may be made separate, and secured upon the bed-plate, as shown.

The upper ends of the standards I I are connected by means of a bar, K, which is bolted to the same, and is for the purpose of a pattern or guide-bar, to guide the tool-stock, and the relative position of the article to be ground, toward the face of the stone.

L represents the tool-stock, of which the central part is made flat, with a straight face, m, upon which the article to be ground is secured.

The remaining ends of the tool-stock, on each side of the central part, are made round, of equal diameter, and are supported and fitted in bearings, M M, in the standards I I, in such a manner that the tool-stock is arranged horizontally, and parallel with the axle C of the stone, and can be turned and will freely slide in these bearings M M.

Now, upon the round part of one side, and close to the central part of the tool-stock, I secure an arm, N, by means of the set-screw n, which arm N extends upward in front of the bar K, in which is fitted a secondary set-screw, o, by means of which the said end of the arm N can be set off, more or less, from the front face of the bar K, whereby the desired relative position of the article to be ground, to the face and periphery of the stone, is adjusted.

O represents a flat spring, which is secured, at p, to the arm N, and bears, with its loose end, against the rear face of the bar K, so that the article to be ground is allowed to yield to inequalities, and is kept bearing, to a proper extent, upon the stone, while sliding along the face of the stone, and being ground.

In order to obtain a regular and proper feed or sliding motion of the article to be ground across the face of the stone, I provide a horizontal shaft, P, which rests, with one end, in the standard J, and is, at its other end, supported in the standard I, which shaft is provided with a screw-thread, r, of the proper pitch, and upon its outer portion, near the standard J, with two fixed pulleys, Q Q, and one loose pulley, R, between.

I also provide a belt-shifter, S, which has upon it two stop-rings, T T, capable of being adjusted and set upon the shifter; and I have a cross-piece, U, arranged vertically across the ends of the tool-stock, the shaft P,

and the shifter S, and fitted with a screw-thread, to work over the screw-thread, *r*, upon the shaft P. Its upper end is attached to the end of the tool-stock L, and is made to pass freely over the shifter S; and I provide, on an extension of the axle C of the stone, as shown, or on a counter-shaft elsewhere, a fixed pulley, V, corresponding, throughout its whole length, with the face of the pulleys Q, Q, and R, which fixed pulley serves to transmit a rotary motion to the shaft P, which motion is obtained by means of an endless belt, W, and is reversed by means of a cross-belt, Y, stretched over the said pulleys Q and V.

By these means, as soon as the grindstone is set in motion, the shaft P is rotated, and, by its screw-thread, draws the cross-piece U and the tool-stock L, and passes the article to be ground across the face of the stone, and, after having passed off the said cross-piece, it acts upon the respective stop-ring T, and moves the one, by means of the shifter S, over to the loose pulley, and the other belt moving, in an opposite direction, upon one of the fixed pulleys, thereby drawing the tool-stock, and the article to be ground, back and forth upon the face of the stone, until the grinding of same is finished.

The central part of the tool-stock L may be made with a slot, *u*, and a clamp, *v*, as shown in figs. 4, 5, and 6; and it may be provided with other means to secure the article to be ground readily and firmly.

To guide the article, in placing it upon the tool-stock,

to a certain desired position, I provide the said stock with guide-pins, *x*, on its face.

For articles, such as planing-irons, shear-plates, &c., in which the edge to be ground is straight, I use a straight guide-bar, K, while, for curved edges, I make and use, instead, a bar which is curved according to the desired edge.

From the foregoing, it will be seen that this device for grinding is of comparatively small expense, and the grinding can be done, with great exactness and precision, by persons incapable of doing so without the aid of the device.

Having fully described my invention,

What I claim therein, and desire to secure by Letters Patent, is—

1. The sliding tool-stock L, in combination with the automatic feed-motion, substantially as and for the purpose described.

2. The sliding tool-stock L, adjustable tangentially with the periphery of the stone, in combination with the arm N and guide-bar K, substantially as and for the purpose specified.

3. The arm N, provided with spring O, and adjusting-screw o, and set-screw n, in combination with the tool-stock L and bar K, substantially as and for the purpose set forth.

Witnesses:

JAMES D. SMITH.
